DESIGN FOR A POKER CHIP OR SIMILAR ARTICLE

Kenneth Tator, Fairfax, Va., and Gustave Holmgren, Washington, D. C.

Application January 11, 1944, Serial No. 112,214

Term of patent 14 years

(Cl. D34—5)

To all whom it may concern:

Be it known that we, Kenneth Tator and Gustave Holmgren, citizens of the United States, residing at, respectively, county of Fairfax, State of Virginia, and Washington, District of Columbia, have invented a new, original, and ornamental Design for Poker Chip or Similar Article, of which the following is a specification, reference being had to the accompanying drawing, constituting a part hereof.

Figure 1 is a face view of a poker chip or simi-

lar article showing our new design, it being understood that the ornamentation shown in the upper half of Figure 1 is continued around the entire periphery of the chip; and

Figure 2 is a sectional view of Figure 1 taken along the line 2—2.

We claim:

The ornamental design for a poker chip or similar article, substantially as shown.

KENNETH TATOR.
GUSTAVE HOLMGREN.
